CHARLES L. LEE, OF DAYTON, OHIO, AND CLAUDE H. STERLING, OF DETROIT, MICHIGAN, ASSIGNORS TO GENERAL MOTORS RESEARCH CORPORATION, OF DETROIT, MICHIGAN, A CORPORATION OF DELAWARE

METHOD OF FINISHING SPLINE SHAFTS

Application filed November 28, 1927. Serial No. 236,218.

This invention relates to spline shafts for carrying the slide gears of an automobile variable speed transmission and for similar purposes; it also relates to the process of finishing spline shafts.

In making spline shafts for use in the transmissions of motor vehicles it is customary to hob or otherwise machine the lands and grooves in a blank of machinable steel, thereafter to heat-treat and harden the machined shaft, and subsequently grind the longitudinal surfaces at the bottoms of the grooves and the sides of the lands. In the heat treating process, more or less distortion is apt to occur, consequently the shaft is originally machined slightly over-size and the excess metal removed by grinding. The irregularities that may be developed by the heat treating and hardening process are smoothed out by the act of grinding. If the shaft is greatly distorted it must be straightened, as in a bulldozing press, or scrapped.

We have ascertained that a superior spline shaft can be made by first machining the blank, leaving a slight excess of metal on the sides of the lands and at the bottoms of the grooves, then heat treating and hardening, and subsequently cold-swaging the shaft from end to end by pressure progressively applied simultaneously between all of the lands,—beginning the swaging operation at one end of the shaft and progressing to the other by small advances.

We have found that shafts bodily distorted and lands warped during heat treating may be straightened bodily and progressively swaged at the same time, as described, and the surface condensed and polished where the slide gears rub upon the shaft, thus producing superior smooth and hard bearing surfaces, and a straight shaft.

In the accompanying drawings, in which like reference characters indicate like parts throughout the several views:

Fig. 1 is a side elevation, partly in section, of a swaging machine adapted to practice this invention.

Fig. 2 is a front elevation of the machine shown in Fig. 1.

Fig. 3 is a front elevation, partly in sec-

tion, the section having been taken on the line 3—3 of Fig. 1.

Fig. 4 is an enlarged view of an individual swaging tool, such as is used in this machine, together with a hammer block and spacing 55 shim assembled with it.

Fig. 5 is an elevation of a conventional spline shaft of the kind used in automobile transmissions.

Fig. 6 is an end elevation of the spline shaft 60 shown in Fig. 5, and

Fig. 7 is a cross section of a fragment of a spline shaft exaggerated in size, after having been swaged.

Referring to the drawings, 10 indicates the 65 base of a swaging machine. Bolted to this base is a bearing standard or shaft hanger 11 having a bearing, and a casting 12 having a bearing opening alined with the bearing in the hanger 11 and also enlarged hollow casing 70 portion 13 which houses the swaging tools and operating mechanism therefor. Extending through the bearing openings in the members 11 and 12 is a hollow shaft 14 which is located longitudinally by pulley 14a fixed 75 to it by collar 15 arranged to engage the outer face of the hanger 11 and a hub 16 formed on a rotary swaging head 17 which is keyed and securely fixed to the shaft 14 at its front end. The shaft and head may be rotated by belting 80 the pulley 14a to a prime mover.

A detachable face plate 18 is secured against a plane, annular surface formed on the front of casing portion 13. This face plate is preferably secured by strong bolts 85 19. The face plate has a tapering opening 18a at the center and has a centrally perforated, swage guide 20 extending into the hollow of the rotary swaging head. Radial, parallel sided guideways 20a are formed in the cylindrical guide 20, said guideways extending from the hollow center through to the exterior surface. In the machine shown there are six of such radial guideways arranged in three pairs, each pair being centrally traversed by the same diametrical plane. In each guideway a swage tool 21 and a hammer block 22 are slidably fitted. Between the swage tool 21 and the hammer block 22 a shim or adjusting plate 23 may 100

be placed, each shim being of the thickness necessary to bring the working face of a swaging tool to the required radial limit. Interposed between the hammer blocks 22 and the inner zone of the rotary head 17 that is intersected by the transverse radial planes of the hammer blocks, is a set of hard rollers 24 properly spaced by a cage 25. The arrangement of swages and operating mechanism causes each swage to be exactly opposed during its working stroke by another swage on the other side of the axis of the shaft 14.

The front sides of the radial guideways in swage guide 20 are open from the zone 26 inward toward the central opening. A door 27, hinged on pintle 28, is provided with a flange 29 adapted to fit against the front of an annular raised surface 30 provided on face plate 18. Into the enlarged and tapering front portion of the opening 18a in said face plate the door projects. Said door carries on its inner face a hard steel plate 31, the inner surface of which serves to close the open side of the guideways and complete the guide in which the swaging tools and hammer blocks are slidably confined. When the door is closed it may be locked by the locking pin 32. The center of the door is open, as shown, to admit the shaft to be swaged when the door is locked. When the door is open the swage blocks may be drawn out through opening 18a and the hammer blocks and shims may then be dropped to the center by gravity or pushed toward the center so that they also may be readily removed.

The working end of each sawging tool 21 is inclined slightly away from the axis of shaft 14 and head 17 from rear to front in order that it may operate upon the shaft subjected to it gradually. As the end of the shaft is inserted into the opening between the swages the front of each swage which is most distant radially from the axis of the shaft, first acts and produces a minute reduction. As the shaft is pushed further inward the portions of the working face of the swage that are nearer to the center of the shaft or the orifice into which it is inserted increase the reduction, the final reduction being made by the inner or rearward edge of the working face. The inclined faces of the swages are indicated in Fig. 1 and also at 34 in Fig. 4. The edges 35 of each swage are sharp, not rounded. When the swaging tools are near the end of their working strokes they squeeze the lands between their inclined faces. The sharp corners or edges at the end of the swages tend to form small shoulders or burrs at 41 by swaging and scraping action.

As shown in Figs. 5, 6, and 7, the shaft is machined with bearing surfaces 38 at the bottom of the grooves, these surfaces being slightly elevated radially leaving small

grooves 39 between the surface 38 and the sides of the lands 40. In the swaging operations the ends of the swaging tools press simultaneously upon the several surfaces 38 and bring them after successive applications of pressure to the desired diameter and polish. The grooves 39 provide space for the metal to flow laterally, and also to receive any metal that may be scraped from the sides of the lands without obstructing the internal angles of the grooves. Fig. 7 indicates on an enlarged scale the spread of the metal toward the grooves 39 after the shaft has been swaged as indicated at 38a and the slight burrs or shoulders 41 formed on the sides of the lands. The metal of the lands being squeezed between opposed swaging dies will be straightened if distorted and metal may flow radially to the slight extent necessary to produce the required result. The finished product is a shaft having highly burnished bearing surfaces on a hard condensed skin produced by heavy pressure applied to the shaft at successive zones throughout its length.

The swaging machine illustrated is of a well known type specifically adapted by the shape of the swaging tools to practice the process of this invention. The blank spline shaft may be inserted through the opening in the door 27 as shown at the right of Fig. 1 and advanced gradually by hand or otherwise between the swaging tools, while the pulley 14a is rotating and communicating rotary motion to the head 17. The hard rollers 24 journaled in the cage 25 are caused to roll by contact with the inner periphery of the head thus causing the cage to revolve with the axes of the rollers moving around the blank at a slower rate of speed than and in the same direction as the head. When the rollers contact with the hammer blocks 22 they press the swages radially inward leaving them free to be moved radially outward after the rollers have passed them until the next rollers engage the hammer blocks.

After completion of the swaging operation no further finishing act is applied except to grind the outer faces of the lands concentric with the axis of the shaft.

By the described process warped shafts are straightened and given a hard smooth accurate bearing surface in the same operation. It is therefore unnecessary to straighten badly warped shafts in a press before finishing, nor is it necessary to provide so much excess of metal as would be required to true badly warped shafts by abrading.

We claim:

1. The process of making spline shafts which consists in first machining a blank of steel to form longitudinal lands and grooves, then heat treating and hardening the shaft and then progressively cold swaging the bearing surfaces from end to end.

2. The process of making spline shafts

which consists in machining a blank of steel so as to form an over-size shaft having grooves and lands, each groove having a bearing surface at its bottom separated from the lands by a longitudinal groove on each side, heat treating and hardening the blank, then progressively cold swaging the hardened blank from end to end between the lands, thereby bringing the shaft to final size, and straightening it.

In testimony whereof we affix our signatures.

CHARLES L. LEE.
CLAUDE H. STERLING.
